UNITED STATES PATENT OFFICE

ANDREW PAYBERG, OF BELMONT, MASSACHUSETTS, ASSIGNOR TO VIKING MANUFACTURING COMPANY, INC., OF CAMBRIDGE, MASSACHUSETTS, A CORPORATION OF MASSACHUSETTS

DISPLAY CARD

Application filed January 18, 1932. Serial No. 537,315.

This invention consists of a display card and framework for the same particularly adapted for use in connection with electric illumination.

5 With the multitude of display cards in use it is of great importance to make the display card as brilliant in appearance as possible so that it may be conspicuous as compared with the display cards with which it is in competition.

10 My new display card and its frame are described in the following specification.

Fig. 1 is a front elevation of a display card containing my invention in place in its frame but pushed partly from the frame to show the construction of the frame and the illuminating features.

Fig. 2 is a somewhat diagrammatic horizontal section on the line 2—2, Fig. 1.

20 Fig. 3 is a somewhat diagrammatic vertical section on the line 3—3, Fig. 1.

Fig. 4 is a fragment of the display card broken away to show the construction.

Any suitable card 1 is cut through with 25 the words or other matter to be displayed as at 2. Back of the openings 2 caused by the design I attach in any suitable manner sheets 3 of transparent cellophane of any desired color or colors. Back of the cellophane I 30 place a backing material 4 of any suitable material, preferably white and translucent if the display card is to be illuminated by transmitted light. The backing paper should not be attached to the cellophane at such 35 points that the glued portion will be apparent from the front. The combination of the outside card with its perforations, the cellophane and the backing material results in a brilliant color display entirely different from 40 a display card from which the backing or the cellophane is omitted. For instance, when viewed by reflected light a display card backed with blue, green, yellow and red cellophane shows little difference between the various colors but when backed with white tissue paper the color by reflected light will be 45 very brilliant blue, green, yellow and red. Viewed by transmitted light colored cellophane shows little color effect unless very 50 deeply colored, but the brilliancy and depth

of the color is remarkably increased when the illumination is transmitted from behind the card through a translucent white backing to and through the cellophane. Thus even by daylight a display card made according to my invention is much more conspicuous than ordinary display cards and the same is true when illuminated at night.

It is a part of my invention, though not necessary under all circumstances, that the display card shall be mounted in a framework 5 supporting an illuminating element such as a number of electric lamps 6, 7, 8 arranged as shown in the drawing. A desirable arrangement of the lights is to place 55 three lamps with different color bulbs, for instance yellow above, blue underneath and red under the blue, six inches more or less back of the display card. These lights may be made to flash in any desired succession for any desired time by a well-known device 9. The walls of the framework are made highly reflecting, as by painting with Sunflex 10 and are set at an angle to the lights and card such that the different parts 75 of the display card are illuminated to a practically identical extent throughout the surface on which the design is to appear. The result is that the colors of the display card will show a startling and brilliant succession of colors by reason of the combination 80 of the colored lamps, the backing paper and the colored cellophane.

My combination gives from these very simple elements a display card which, so far as I 85 know, is unequalled in conspicuousness.

Cellophane is a well-known trade name for a material, made by one manufacturer, which I am informed is principally cellulose produced from cellulose xanthate. I have used 90 the term here to denote any cellulosic material having practically equivalent properties as regards the reflection and transmission of light though made by other manufacturers.

I claim:

The combination of a framework and means for holding the display card in the front part thereof, of electric lamps one above the other and four flat reflecting surfaces mounted in said framework, said surfaces 10

being arranged to direct the light from the lamps so as to illuminate the design to be displayed at all points, whether one or all of the lights are lit, the display card having a design cut through the same backed with colored cellophane and a white paper backing inside the cellophane whereby the design is displayed in color both by day and night.

ANDREW PAYBERG.
